UNITED STATES PATENT OFFICE.

FRANK O. WOODLAND, OF WORCESTER, MASSACHUSETTS; FRANCES S. WOODLAND AND ARTHUR F. KELLEY, ADMINISTRATORS OF SAID FRANK O. WOODLAND, DECEASED, ASSIGNEES TO ECONOMIC MACHINERY COMPANY, OF WORCESTER, MASSACHUSETTS, A CORPORATION OF MASSACHUSETTS.

FEEDING MECHANISM FOR LABELING-MACHINES.

1,199,516.

Specification of Letters Patent. Patented Sept. 26, 1916.

Application filed September 27, 1915. Serial No. 52,774.

To all whom it may concern:

Be it known that I, FRANK O. WOODLAND, a citizen of the United States, residing at Worcester, in the county of Worcester and State of Massachusetts, have invented certain new and useful Improvements in Feeding Mechanism for Labeling-Machines, of which the following is a specification.

My present invention relates to the construction and arrangement of feeder mechanism for transferring bottles, or similar articles or containers, from a delivering conveyer to the continuously moving carrier in an automatic labeling machine; the objects 10 being to render the mechanism more satisfactory and efficient, and to provide a feeder device in which the feeder-fork, or pushing member, is adapted to have a longitudinal reciprocative action relatively to the feeder- 15 arm or element, upon which it is supported, and means for controlling the respective movements of said parts.

Another object is to provide means for operating said feeder element and its end- 20 wise reciprocating fork or pushing member by, or in connection with the bottle carrier, and arranged to be non-operative in respect to the reciprocation of said fork unless a bottle or the like is in position to receive its 25 action.

My invention consists in a mechanism embodying the features of improvement set forth and fully explained in following detailed description and illustrated by the 30 drawings; the particular subject matter claimed being hereinafter definitely specified.

In the drawings, Figure 1 represents a front view of an automatic feeder mechanism embodying my invention. Fig. 2 is a 35 plan view of the same, some of the parts being indicated by dot and dash lines, or in section, the better to reveal the forms of underlying portions. Fig. 3 represents a 40 separate plan view of the tripping catch. Fig. 4 is a fragmentary plan view of the cam-engaging rollers. Fig. 5 is a front view of the cam devices at the front edge of the 45 rotary carrier, and Fig. 6 is a plan view 50 illustrating the action of the mechanism.

Referring to the drawings, the numeral 12 indicates the rotary table or carrier upon

which the bottles or like articles are advanced for being labeled; 13 indicates the traveling conveyer for bringing the bottles 55 or articles from any convenient distance to the transfer passway 10 and barrier 15, the upper portion of the latter being shown by dash and dot lines on Fig. 2. 16 and 17 indicate upright guards or fenders defining 60 the path within which the bottles or articles are carried forward, and 14 is one of the bottle pusher rests. These enumerated parts may be severally constructed and combined to operate in the manner heretofore employed in labeling machines of the character 65 described in Letters Patent Number 1,113,854 heretofore granted me; but are herein shown to better illustrate the adaptation, to such machines, of the improvements 70 which constitute the subject matter of invention hereinafter claimed.

In accordance with my present invention the feeder mechanism comprises a main arm, lever, or body member 20, having a suitable 75 bearing hub 22 at one end mounted to swing upon an upright axis or stud 19 fixed in the machine frame 1. Said arm is preferably provided at its other end with a rigidly attached horizontally curved prong 21 projecting from its upper side and extended 80 partially across the passway 10 through which the bottles or the like are fed. A bottle-engaging fork or member, comprising a longitudinally disposed rod 23 having a 85 broad furcate head, is mounted to have endwise reciprocative action in bearings 5 and 6 upon the main arm 20, and is furnished with a spring 24, preferably a push spring coiled about the rod, for normally 90 projecting the head of the fork at the outer end of the main arm, as shown in Figs. 1 and 2.

The feed-fork is preferably formed with straight upper and lower parts 2 and 3 at its head having finished surfaces which fit and slide smoothly within the guiding bearings 5 upon the arm 20, while the rear end of the rod 23 is arranged to slide within the guiding bearing 6 adjacent to the fulcrum hub 22, which latter bearing serves as an abutment for the end of the spring 24.

The arm 20 has, at an intermedial position thereon, a projection or ear in which a de-

pending stud 25 is fixed. A roller 26 is arranged upon said stud and runs against a cam surface 27 upon the edge of the carrier 12 for controlling the movement of the arm; 5 said arm being constantly pressed forward to keep the roller 26 against the cam 27 by the pull spring 28 that is connected with a projecting member or lug *c* formed upon the arm, and with an anchor device *a* secured 10 to the frame. The delineation of the inter-medial portion of this spring 28 is omitted on the present drawings, the better to reveal underlying parts.

Supported upon the stud 25, adjacent to 15 the roller 26, I arrange a hub 30 carrying an arm 31 that is connected by a link 32 with the head of the feed-fork 23 by a pivot joint at 33. Also, in connection with the hub 30, 20 I provide an eccentrically disposed member, and cam-engaging roller 36, that forms the opposite arm to the lever of which the arm 31 is a part, and the hub is the fulcrum piece; said roller being preferably adapted to be shifted up or down to bring it into or 25 out of operative alinement with its actuating means. As illustrated, (see Figs. 1 and 4) these parts are arranged as follows: The hub 30 has connected therewith by a horizontal hinging joint 34, a bracket or sup- 30 porter 35, having the cam-engaging roller 36 mounted upon a suitable axis stud fixed in said supporter, eccentric to the axis of the depending stud 25. Said roller 36 is 35 permitted by the horizontal hinging action, to be brought up to a normal working position adjacent to and parallel with the roller 26, or dropped to a lower inclined position. A stop-guard 37 is provided for arresting 40 the upward swing of the roller when at a position with its plane perpendicular to the axis of the stud. The roller is adapted for engagement, when elevated, with a series of cam-devices 39 fixed upon the rotary carrier 12, and for escaping contact with said 45 cam-devices when it is swung downward on its hinges 34. By the action of the cam-device 39 against the roller a partial rotation of the hub 30 is effected, swinging the arm 31 and drawing back the link 32, there- 50 by producing an endwise retractive move- 55 ment of the feed-fork in opposition to the pressure of the spring 24, which latter returns the parts to their primal position when the roller 36 is released by the cam-device.

The roller 36 is elevated from its idle position into alinement with the cam-devices 39, by suitably disposed inclined guides 40 connected with the carrier 12, which pass 55 under the free end of the hinged supporter 35 and swing it up into level relation with the cam 39. These inclined guides 40 are so placed that the roller support 35 will not 60 contact therewith unless the main arm 20 has started to swing inward and moved to

such a predetermined degree as will bring the roll-supporter laterally into coacting re-lation. Hence, when there is no movement of the main arm there will occur no retrac-tive movement of the feed-fork. At the 70 rear end of the cam member 39 there may be arranged a depressor flange 41 for throwing the supporter and roller 36 down to their low position before encountering the next succeeding set of cam-devices in the series. 75

Numeral 42 indicates the tripping catch, which is arranged beneath the fore end of the main arm or lever 20, pivoted at its outer end to the stationary frame by the fulcrum stud 43, and provided with a spring 45 80 which tends to return the catch-device to primal position. Said catch-device may be made as shown in Fig. 3, with an upstand-ing lip or flange 7 facing the conveyer 13, and against which the bottles or the like 85 contact as they come into position for trans-fer; also with a lug or member 8 that en-gages with a coacting lug 9 formed on the main arm, for retaining said arm at its out-ward position excepting when the catch is 90 released by swinging back the catch-device, which is effected by contact of the approach-ing bottle therewith, as heretofore practised. The lugs 8 and 9 may be arranged for lock-95 ing the catch against tripping action until the main arm is moved slightly backward; such feature, however, was described in my previous Letters Patent, but by other con-structed means.

The feed-fork is preferably provided upon 100 its lower fork-member 3 with an outstand-ing flange or guard-plate 47 having an in-clined outer edge. The purpose of said flange is for warding off pieces of broken glass, or any solid obstruction that might 105 accidentally interfere with the action of the feed-mechanism.

In the operation: When a bottle or the like, brought in upon the traveling conveyer 13, contacts with and pushes back the catch 110 42, the arm 20 is released and the depre-sion in the cam surface 27, against which the roller 26 runs, permits said arm to be 115 swung forward by the force of the spring 28; the extended ends 2 and 3 of the feed-fork engaging behind the bottle and propelling it through the passway 10 from the conveyer onto the rotating carrier 12, where is is carried forward as usual. During the 120 movements of the main arm and rotation of the carrier, the guide 40 passes under the hinged supporter 35 and lifts the roller 36 into alinement with the cam 39, which latter presses back the roller 36 swinging the hub 30 and arm 31; so that the endwise slid-able 125 feed-fork is retracted or moved, so that its head or furcated members 2 and 3 do not project into the passway 10 as the arm swings back to its primal position; then the cam 39, leaving the roller 36, permits the 130

feed-fork to be re-projected to its outward position by action of the spring 24.

What I claim and desire to secure by Letters Patent, is—

- 5 1. An automatic feed mechanism for labeling machines comprising, in combination with a rotating carrier upon which bottles or the like are carried to label-applying mechanism, a delivering conveyer, and a laterally movable feeder-arm; of an endwise reciprocating bar, its head adapted for pushing a bottle or the like from the conveyer to the carrier, means actuated from the carrier for retracting said bar during the backward movement of the feeder-arm; and means for projecting said bar to engage the bottle during the forward movement of the feeder-arm.
- 20 2. In a mechanism of the character described, the combination with a bottle-carrier, a bottle-delivering conveyer having a barrier and passway therefrom to the bottle-carrier, a feeder-means including an arm pivoted to swing across the conveyer, and having a backward curved outwardly projecting prong, a projectable pusher member supported upon said arm and endwise slideable to and from projecting relation, a spring for normally projecting said pusher member, a connection and actuating means therefor operatively controlled by cam-devices that move with the bottle-carrier, a spring for yieldingly advancing said arm, and means for positively moving said arm backward in opposition to the force of the spring.
- 25 3. In combination with a bottle-delivering conveyer, and a rotary carrier to which the bottles are shunted, a bottle-shunting mechanism, including a swinging supporting-arm, and an endwise extendable and retractable bottle-actuating element mounted thereon in approximately lengthwise relation to the arm, and means for actuating said parts.
- 30 4. In a mechanism of the class described, in combination with a rotary carrier and a delivery conveyer having a pass-way leading to said rotary carrier; of a feeder device including a movable supporting element carrying a projectable member adapted for telescoping action, means for operating the feeder device, and means for effecting extension of the projectable member to control the passway during its forward action, and means for its retraction to relieve the passway during the backward action of said feeder device.
- 35 5. A feeder mechanism, including a swing-ing arm pivoted at its rear end, and having a contact member for engaging an actuating means, an endwise movable rod mounted in said arm and having a head for engaging with the bottle, a spring for projecting said head, a connection for retracting said head, means for actuating the retractor, and

a cam upon the bottle-carrier engaging said contact roll, substantially as set forth.

6. In a feed mechanism for the purpose set forth, the combination, of a laterally swinging arm pivoted at its rear end and having at its fore end a curved prong that projects in front of the bottle or the like, an endwise movable bottle-engaging fork mounted in bearings upon said swinging arm, moving therewith, and adapted for projection behind the bottle, means for retracting said fork out of reach of the bottle, means for actuating the swinging arm, and means for imparting reciprocative action to the bottle-engaging fork.

7. In a mechanism of the character described, the combination with a rotary bottle carrier, an oscillating feeder arm provided with a depending stud having a cam-engaging roller mounted thereon, and an endwise movable feeder-fork mounted in guides on said feeder arm; of a fork-retracting lever having a hub mounted on said depending stud, a shiftable eccentrically located cam-engaging roller, a supporter for said roller laterally hinged to the hub of said lever to move up and down, cam-devices moving with the bottle-carrier for actuating said lever, and inclined guide flanges in connection therewith for shifting said cam-engaging roller into alinement with said actuating cam-devices.

8. A feeder mechanism for the purpose specified, comprising an oscillatable body element fulcrumed at one end and provided with an intermediately disposed cam-engaging member, a feeder means longitudinally movable in guides upon said body element, a spring for normally projecting said feeder means for actuating a bottle or the like, a retracting lever carried upon said body element and connected with said feeder means; a shiftable cam-engaging roller connected with said lever, actuating cams for individually controlling the movement of said body element and said feeder means, springs for yieldingly forcing or moving said body element and feeder-means in their operative action, and means for shifting said cam-engaging roller into alinement with its actuating cam.

9. A feeding mechanism for the purpose set forth, comprising a body element pivotally supported near one end, and having a spring attaching ear and an intermediately disposed stud, a roller mounted on said stud for contact with an actuating cam, a bottle feeder member longitudinally movable in guides upon said body element, a spring for normally projecting said feeder, a swinging lever fulcrumed on the body element and having an arm connected with said feeder member, its other arm carrying a cam-engaging roller, cam surfaces for individually controlling the movements of said

80

95

110

120

125

130

body element and feeder member, and a spring connected with said body element for pressing it toward its controlling cam.

10. In a mechanism of the character described, a main swinging feeder arm having a stud fixed therein, a cam-engaging roll upon said stud, a reciprocating feed-fork carried on said arm, an actuating spring and retracting lever for said fork, and a hingingly attached roll-supporter carrying a roller and connected with said lever; in combination with a bottle-carrier table having cam surfaces adapted for contact with the roller on said main feeder arm, and auxiliary cam devices that engage the roller connected with said fork-retracting lever, said cam-devices relatively located to engage the roller when

the main feeder arm is in normal operation, but to escape said roller when the main feeder arm remains unactuated, substantially as set forth.

11. In a feeder mechanism of the class described, in combination with a delivery conveyer terminating with a barrier and pass-way, and a laterally moving feeder element adjacent said carrier, of an endwise movable feed-fork slidably mounted in bearings upon said feeder element, and provided upon its head with an outstanding guard flange having a backwardly inclined edge, means for actuating said feeder element, and means for independently imparting endwise shift to said feed-fork.

FRANK O. WOODLAND.
